LIQUID ACID-DETERGENT-SANITIZER
COMPOSITIONAndrew B. Law, Levittown, Pa., assignor to Rohm & Haas Company, Philadelphia, Pa., a corporation of Delaware
No Drawing. Filed Nov. 12, 1964, Ser. No. 410,705
5 Claims. (Cl. 252—106)

This application is a continuation-in-part of my application Serial No. 146,014 which was filed on October 18, 1961, and which has since been abandoned.

This invention relates to a liquid acid-detergent-sanitizer of high hard water tolerance. It has particular reference to a formulation containing a quaternary ammonium composition as the sanitizer and a nonionic as the detergent.

One of the principal components of the present invention is an outstanding commercially available sanitizer which consists of an aqueous solution of a mixture of alkyl dimethyl benzyl ammonium chlorides. The mixture consists of alkyl dimethyl benzyl ammonium chlorides whose alkyl groups can range from C_8 to C_{18} , although its most effective germicidal components are those whose alkyl groups are C_{12} (lauryl or dodecyl), C_{14} (myristyl or tetradecyl) and C_{16} (cetyl or hexadecyl). The proportions of the C_8 — C_{18} components can vary, depending upon the manufacturer and the particular batch of the product. However, for the purposes of the present invention the proportions are not critical, the sanitizer being effective in the various proportions, some to a greater and others to a lesser degree, in the invention as described hereinbelow.

One of the most outstanding features of this conventional quaternary sanitizing composition is its exceptional effectiveness in hard water. The sanitizing dilution for quaternaries is considered "standard" in the United States and in most foreign countries is 200 p.p.m., and in many states and local governments this requirement is specified by law. At this dilution the hard water ceiling for the quaternary described above is 550 p.p.m. hard water. This means that the quaternary is capable of killing 99.999 percent of specified test organisms (generally *Escherichia coli*), in 30 seconds, in water containing up to 550 p.p.m. (32 grains per gallon) hardness calculated as $CaCO_3$.

The test method used is the Chambers modification of the Weber-Black technique as described in "Methods of Analysis of the Association of Official Agricultural Chemists (AOAC)," 9th Edition, 1960 (as originally described in the Journal of that association, vol. 41, No. 1, 1958). In accordance with this procedure an inoculum containing a known number of bacteria is added to hard water solutions of the acid-detergent-sanitizer formulations. Aliquots of the solutions are then removed at timed intervals and the quaternary inactivated by diluting 1:10 with a lecithin-Tween 80 solution known commercially as "Lethen." "Tween," a product of the Atlas Powder Company, Wilmington, Delaware, is a fatty acid ester of anhydrosorbitols which have been solubilized by etherifying the free hydroxyl groups with ethylene oxide. Agar pour plates are prepared from the Lethen solutions, incubated at 37° C. for 48 hours and counted for surviving bacteria.

In copending application Serial No. 146,016, filed by me on October 18, 1961, and now abandoned, it was disclosed that some detergents employed with the sanitizer described above greatly reduced the high hard water tolerance of the quaternary. In fact, the invention in that case was the discovery that certain ethoxylated t-carbinamines were the only surfactants that did not so lower the high hard water tolerance. It was also disclosed

2

therein that the described combination of detergent-sanitizer was quite compatible with alkali.

There are many applications in which it is desired to employ a detergent-sanitizer under conditions where acid, such as phosphoric acid, was present and the composition had a pH of about 2.5—3.0. However, it has been observed that the presence of phosphoric acid reduces the rate of kill of the alkyl dimethyl benzyl ammonium chloride sanitizers at certain low water hardness levels, and this fact has made the provision of a satisfactory acid-detergent-sanitizer using this combination of acid and quaternary most improbable. It is, therefore, a surprising discovery to have found that a highly compatible acid-detergent-sanitizer incorporating phosphoric acid and the described sanitizer can be made without adversely affecting either the high hard water ceiling of the quaternary or reducing its rate of kill in water of low hardness, by employing as the detergent a certain class of alkylaryl polyether alcohols. This class includes octyl and nonyl phenoxyethoxyethanols having from about 5 to 7.5 ethylene oxide units, and polypropyleneoxypropyl, octyl or nonyl phenoxyethoxyethyl ethers having the structural configuration

25

in which R equals a C_8 — C_9 alkyl group, $x=5$ to 7.5, and $y=10$ to 15. The class of detergents used is critical to the successful operation of the acid-detergent-sanitizer. This is well illustrated below where evidence is given of a large number of otherwise excellent detergents which were tried in combination with the same acid and sanitizer, but were unacceptable because of the adverse effect they had on the hard water ceilings or floors, as the case may be.

Keeping in mind the requirement that to be satisfactory an acid-detergent-sanitizer must not only have an adequate hard water ceiling, but the detergent in the composition also must not reduce the rate of kill of the germicide in the composition when the composition is employed in water of low hardness. In other words, the composition must not produce a "hard water floor." This "floor" may be described as that hardness, in number of p.p.m. of a synthetic hard water, below which the 200 p.p.m. of active quaternary formulation does not kill 99.999 percent of the inoculum in 30 seconds, but above which the required kill of inoculum is obtained. Put another way, the formulation could pass the Chambers test above 300 p.p.m. water hardness but not below this level of hardness.

In Table I, which follows, there are listed a number of detergents, almost all of them commercially well-known, which were tested for compatibility with the hard water tolerance of the sanitizer described above (C_8 — C_{18} alkyl dimethyl benzyl ammonium chloride composition) in a phosphoric acid environment. The use ratios were the preferred minimal amounts, namely 200 p.p.m. of the sanitizer and 200 p.p.m. of the detergent, plus sufficient phosphoric acid to bring the pH of the solution to between 2.5 and 3.5. Generally, the amount of phosphoric acid needed to attain a pH within this range is between 200 and 900 p.p.m. Of course, if more sanitizer and detergent are employed more acid will be required. Keeping within the indicated pH range is critical to the successful operation of the invention when it is desired to produce compositions which will have both satisfactory "ceilings" and satisfactory "floors." In preparing the compositions, incidentally, the desired amounts of the acid, detergent and sanitizer were mixed together, and the balance made up to mark by addition of distilled water.

TABLE I

Detergent No.	Chemical Composition	Ethylene Oxide or Propylene Oxide Content (Moles)
1.	Benzyl ether of octyl phenoxy polyethoxyethanol.	EO 16.
2.	Polypropyleneoxypropyl octylphenoxypolyethoxyethyl ether.	EO 8.8; PO 4.5.
3.	Octylphenoxy polyethoxyethanol.	EO 9.7.

5.	Octyl phenoxy polyethoxyethanol.	EO 16.
6.	do.	EO 20.
7.	do.	EO 30.
8.	do.	EO 5.
9.	Cetyl stearyl polyethoxyethanol.	EO 30.
10.	Polyethylene glycol monoether of octyl phenol formaldehyde condensation product (25% H ₂ O solution).	EO 11.
11.	Octyl phenoxy polyethoxyethanol.	EO 12.5.
12.	Sodium salt of sulfated t-C ₁₁ - ₁₄ H ₂₃ - ₂ NH(CH ₂ CH ₂ O) ₁ H.	EO 5.
13.	Sulfated t-C ₁₁ - ₁₄ H ₂₃ - ₂ NH(CH ₂ CH ₂ O) ₁ H.	EO 15.
14.	n-Dodecyl amine.	
15.	Nonylphenoxy polyethoxyethanol.	EO 8.5.
16.	Methylene bis-diannylophenoxy polyethoxyethanol.	EO 8-10.
17.	Octylphenoxy polyethoxyethanol.	EO 7.5.
18.	Dinonyl phenoxy polyethoxyethanol.	EO 21.
19.	Polypropyleneoxypropyl octylphenoxypolyethoxyethyl ether.	EO 7.5; PO 13.

In Table II, which follows, there are shown a number of detergents identified in Table I and their effect upon a solution containing 200 p.p.m. of the C₈-C₁₈ alkyl dimethyl benzyl ammonium chloride sanitizer described

above, and 400 p.p.m. of phosphoric acid. In all cases the concentration of the detergent was 200 p.p.m. In one instance this concentration was arrived at by using 100 p.p.m. of each of two detergents.

TABLE II*

NOTES:

*Elapsed time in all of the above experiments was 30 secs.

†This composition formed from one-half of No. 7 and one-half No. 4.

TS=Total survival, number of bacteria/ml.

It will be seen from the data in Table II that only detergents Nos. 8, 17 and 19 met the hard water ceiling specification of the Chambers (Weber-Black) test described above at all hardnesses examined, when in combination, as shown, with the acid and sanitizer. The same three detergents also showed no appreciable hard water floor in waters of 250 p.p.m. of lower hardness levels, as shown in Table III below.

TABLE III*

Detergent No. (from Table I)	Water Hardness in p.p.m.					
	50	100	250	500	750	1,000
8-----	TS/ml.....	0	0	0	0	0
	Percent Kill.....	100	100	100	100	100
17-----	TS/ml.....	1,430	440	0	0	470
	Percent Kill.....	99.9985	99.9995	100	100	99.9995
19-----	TS/ml.....	0	0	0	0	0
	Percent Kill.....	100	100	100	100	100

NOTE.—*Effect of a solution containing 200 p.p.m. of the C₈-C₁₈ alkyl dimethyl benzyl ammonium chloride sanitizer described above, and 400 p.p.m. of phosphoric acid. In all cases the concentration of the detergent was 200 p.p.m., and the elapsed time of each experiment was 30 seconds.

For the sake of comparison, the data in Table IV show the effect which occurs when the same quantity of phosphoric acid (400 p.p.m.) is mixed with the same quantity (200 p.p.m.) of the same sanitizer as in the previous tables. For a further comparison, the data in Table V show the effect which occurs when the same quantity of the acid and the same quantity of the sanitizer are mixed with one of the best known and most efficient prior art detergents, namely No. 3 in Table I.

TABLE IV†

Detergent	Water Hardness in p.p.m.

NOTE.—†=Elapsed time 30 seconds.

TABLE V‡

Detergent No.	Water Hardness in p.p.m.				
	50	100	250	500	1,000
3-----	TS/ml.....	325,000	49,800	2,460	15,600
	Percent Kill.....	99.6453	99.9470	99.9974	99.9834

NOTES:

*TNC=Too numerous to count.

†=Elapsed time 30 seconds.

As Table IV shows, the combination of the acid and the sanitizer produces a floor at each of the three levels of

water hardness tested. Table V shows that merely the addition of a detergent, even one of the best prior art detergents, will not eliminate the floor (or raise the ceiling). It takes the right combination of acid-detergent-sanitizer, as discussed just before Table I and as shown in Tables II and III, to provide a fully compatible system, one which is suitable with regard to both the ceiling and the floor of the formulation. This combination is critical to the successful operation of the invention, and is, therefore, precisely what I have defined in the claims set forth below.

I claim:

1. A liquid acid-detergent-sanitizer composition consisting of phosphoric acid, a C₈-C₁₈ alkyl dimethyl benzyl ammonium chloride sanitizer, and an alkylaryl polyether alcohol detergent from the class consisting of octyl and nonyl phenoxyethanols having an average of from about 5 to about 7.5 ethylene oxide units, and polypropyleneoxypropyl octyl and nonyl phenoxypropoxyethoxyethyl ethers having the structural configuration

in which R= a C₈-C₉ alkyl group, x= 5 to 7.5 and y=10 to 15, the amounts of said sanitizer and detergent being in substantially a 1:1 ratio, and the amount of phosphoric acid being in sufficient quantity to give a pH of between about 2.5 and 3.5, said ratio and pH being in effect when the composition is diluted with water so as to contain between 200-900 parts per million of the acid and at least about 200 parts per million each of the sanitizer and of the detergent.

2. The composition of claim 1 in which the sanitizer is a mixture principally consisting of C₁₂, C₁₄ and C₁₆ dimethyl benzyl ammonium chlorides.

3. The composition of claim 1 in which the alkylaryl polyether alcohol is octylphenoxypropoxyethoxyethanol in which the ethylene oxide content averages about 7.5 moles.

4. The composition of claim 1 in which the alkylaryl polyether alcohol is octylphenoxypropoxyethoxyethanol in which the ethylene oxide content averages five moles.

5. The composition of claim 1 in which the alkylaryl polyether alcohol has the structural configuration
